Attorneys

UNITED STATES PATENT OFFICE.

WILMER J. GERBER, OF DEADWOOD, SOUTH DAKOTA.

OIL-TUBE CLEANER.

Application filed July 20, 1922. Serial No. 576,879.

To all whom it may concern:

Be it known that I, WILMER J. GERBER, a citizen of the United States, residing at Deadwood, in the county of Lawrence and State of South Dakota, have invented certain new and useful Improvements in Oil-Tube Cleaners; and I do declare the following to be a full, clear, and exact description of the invention, such as will enable others skilled in the art to which it appertains to make and use the same.

My invention relates to improvements in devices for cleaning out the oil tubes of automobile engines, by means of fluid under pressure, the object being to provide an extremely simple and inexpensive device which may be quickly and easily applied, simply by removing one of the cover plates of the usual oil pan.

A further aim is to provide a cleaning device of the character described which is adapted to be interposed between the front end of the oil tube and one of the timing gears or any other suitable part spaced from the tube, being provided with means to engage this part so as to hold the cleaner in place while forcing fluid under pressure therethrough to clean the tube.

With the foregoing in view, the invention resides in the novel subject matter herein-after described and claimed, the description being supplemented by the accompanying drawing.

Figure 1 is an elevation partly in section of a common form of automobile motor, showing the application of my invention.

Figure 2 is an enlarged sectional view partly in elevation showing more clearly the manner in which the oil tube cleaner is held in place.

Figure 3 is an enlarged side elevation of the cleaning device.

Figure 4 is a transverse sectional view as indicated by line 4-4 of Fig. 3.

In the drawing above briefly described, the numeral 1 designates an L-shaped connection, one of whose arms 2 is preferably in the form of a tube section for connection with a suitable hose or the like 3 for supplying fluid under pressure. If desired, the arm 2 may well be threaded on its outer end for engagement with the usual connection on the hose of an ordinary tire pump. The other arm 4 of the connection 1 is preferably cast but may be other-

wise formed, this arm being so shaped that it may be easily interposed between the oil tube 5 of an automobile engine and a part spaced from the end of said tube, for instance one of the timing gears 6. In the present showing, the inner side of the arm 4 is of substantially conical form at its outer end as indicated at 7 so as to be easily engageable with the end of the oil tube, insuring that the passage 8 which is formed through said arm for communication with the passage of the arm 2, shall be properly aligned at the discharge end, with the tube 5.

To retain the connection 1 in place, while fluid under pressure is being forced therethrough to clean the tube 5, I provide said connection with means to engage the timing gear 6 or some other suitable part of the automobile motor, said means being here shown in the form of a spring 9 carried by the arm 4, the free end of said spring being self-projectable from the outer side of said arm prior to applying the device to the machine. When its use is needed, in order to apply the device, it is simply necessary to remove one of the usual oil pan covers, whereupon the connection 1 may be inserted into the oil pan and positioned between the tube 5 and the timing gear 6 or other desired part. The spring 9 engages this part and detachably holds the arm 4 in proper relation with the tube 5 while fluid under pressure is being used to clean said tube.

From the foregoing, it will be seen that a badly clogged oil tube may be quickly and easily cleaned by the use of my invention. Since probably the best results may be obtained from the details shown, they may well be followed, but it is to be understood that within the scope of the invention as claimed, numerous minor changes may be made. For instance, while I have shown the arms 2 and 4 formed of separate pieces having a threaded connection 10 with each other, it will be understood that these arms might be otherwise connected and in fact they might be formed as a single piece if desired.

I claim:

1. An oil tube cleaner for automobile engines comprising a removable fluid supply connection adapted to be interposed between the outlet end of the oil tube and a part spaced from said outlet end of said tube, said connection having means to en-

gage said part and hold the connection in place while forcing fluid under pressure therethrough to clean the tube.

2. A tube cleaner comprising a connection adapted to be removably engaged with the outlet end of the tube, and a spring device for holding said connection in engagement with said tube, said connection having a passage for supplying fluid under pressure to the tube.

3. A structure as specified in claim 2, said passage opening in one direction, said spring device being carried by said connection and being self-projected in the other direction until engaged with a fixed part spaced from the tube end.

4. A tube cleaner comprising an L-shaped connection having a fluid pressure passage from the outer end of one arm to the outer end portion of the other arm and opening laterally through the inner side of the latter, said inner side of said last named arm being adapted to engage the outlet end of a tube and center the passage with respect thereto, and a spring device carried by said connection to engage a part spaced from the tube, said spring device being self-projectable beyond the outer side of said last named arm.

In testimony whereof I have hereunto affixed my signature.

WILMER J. GERBER.
